A method of transmitting signals in accordance with the present invention, the method comprising the steps of: applying an alternating voltage to the anode of a high vacuum tube, said tube having a grid, the anode potential being controlled by a modulating signal, the anode potential being displaced by a value $\alpha\delta E_A$ when the anode potential varies by the value δE_A whereby a corresponding variation of the high frequency amplitude is produced. Therefore in order to obtain such a displacement of the working point it is necessary to have a large amplification factor reciprocal, in order to obtain at changing anode potential an effective action upon the high frequency current. Thus in the hitherto known arrangements

MODULATION

Otto Böhm, Berlin, Germany, assignor to Tele-funkens Gesellschaft für Drahtlose Telegraphie m. b. H., Berlin, Germany, a corporation of Germany

Application October 27, 1933, Serial No. 695,396

In Germany October 12, 1932

1 Claim. (Cl. 179—171)

The present invention relates to modulated transmitters and in particular to telephony transmitters.

It is known in the art that in order to insure current economy in the operation of a telephony transmitter, said telephony transmitter may be operated in such a manner that the mean carrier wave amplitude is changed in accordance with changes in the volume of the speech or music to be impressed thereon and that the modulated waves as transmitted are of an approximately constant degree of modulation with respect to time. To accomplish this it is possible, for instance, to use transmitter circuits in which the anode direct current potential supplying the final stage serving as the modulating stage is controlled. Such an arrangement has two favorable features, the first of which is that, when the amplitude of the modulating frequency decreases the mean amplitude of the produced carrier wave is reduced due to the simultaneous decrease of the direct anode current potential. In addition in decreasing the direct anode potential, the anode losses are likewise reduced due to the decrease in the anode zero or no modulation current. For this known method in the controlled stage, only tubes having a large "durchgriff" (through grip of the plate on the electrons between grid and cathode)

30

$\left(\frac{1}{\mu}\right)$

are suitable, the modulated tubes oscillate at reduced tension, meaning the alternating voltage amplitude superposed upon the anode potential is always small as compared with the anode direct current potential, and the change of the direct current anode potential in tubes having a small "durchgriff" (reciprocal of the amplification factor)

$\left(\frac{1}{\mu}\right)$

would not cause an appreciable variation of the high frequency amplitude. It is merely due to the "durchgriff" that the working point is displaced by a value $\alpha\delta E_A$ when the anode potential varies by the value δE_A whereby a corresponding variation of the high frequency amplitude is produced. Therefore in order to obtain such a displacement of the working point it is necessary to have a large amplification factor reciprocal, in order to obtain at changing anode potential an effective action upon the high frequency current. Thus in the hitherto known arrangements

which aimed at a wide control of the amplitude of the carrier wave, tubes having a large amplification factor were of necessity. On the other hand the method of transmitting waves of approximately constant degree of modulation with a controlled carrier wave has the disadvantage that if it does not operate over the entire modulation range with but a small control of the carrier wave which small control, however, is opposed to the desired effect of current economy, the receiver used to demodulate said controlled wave is required to be substantially distortionless in operation. Such transmitter can ordinarily only be received with strong distortion.

According to the present invention in order to obtain an economically operated transmitter the aim is, in the first place to avoid anode losses instead of effecting radiation of waves of constant degree of modulation. In accordance with the invention the power amplifier tubes primarily used in the transmitter output stage consist of high gain tubes having a small amplification factor reciprocal

$\left(\frac{1}{\mu}\right)$

25

(below 5%), and the direct current anode potential for these tubes is controlled according to the respective amplitude of the modulation oscillations. The use of tubes having a small amplification factor reciprocal in transmitter output stages is known as such but it becomes of novel technical importance in connection with the variation of the direct anode potential controlled by the sound intensity of the modulation. The control of the supplied direct current voltage is suitably obtained by using rectifiers provided with control electrodes and which produce the anode potential by rectifying energy from an alternating current source. The control electrodes, in order to vary the supplied current voltage, are influenced in accordance with the amplitude of modulation potentials.

The accompanying drawing shows an embodiment of the invention by way of example.

45

A designates the antenna to which the transmitter oscillations are supplied from the output circuit of the transmitter tube E. The tube E receives the high frequency control oscillations from a high frequency source H. The anode of the tube E is fed by direct current potential. The direct current anode potential is produced by means of a transformer T connected with a source of alternating current on the one hand and to a rectifier tube G provided with a control

50

55

grid on the other hand. Filtering means D_1 , C_1 , C_2 is interposed between the anode of E and the rectifier output. The cathode of the last tube E , having a small amplification factor reciprocal, for instance, a screen grid tube, is blocked by means of a blocking condenser C_3 bridged by the secondary winding of the transformer T_2 serving to supply modulating currents from the source M to the grid of the tube E . The primary winding of T_2 is coupled to the microphone circuit M . Furthermore, parallel to the secondary winding of the transformer T_2 a rectifier tube K has its anode to cathode impedance connected in series with a blocking condenser C_4 bridged by a resistor R . Under the influence of the modulating currents voltages are produced at the condenser C_4 , the value of which corresponds with the peak voltage of the audio frequency currents. These voltages on the one hand are supplied to the grid electrode of a tube V operating in the bend portion of its characteristic. The anode of the tube V is likewise fed from the line transformer T_3 coupled to the grid cathode circuit of the rectifier tube G . In this manner a suitable bias is produced at the grid of the rectifier tube G representative of the amplitude of the modulating oscillations and thus the anode potential of the tube E is controlled in accordance with the amplitude of the modulating circuits. The tube G

may be of the type in which initiation of current flow is dependent on grid potential reaching a certain value, continues irrespective of grid potential changes, and is terminated only by falling off of anode potential below a predetermined value. 5

Having thus described my invention and the operation thereof, what I claim is:

In a telephony signalling system, a thermionic tube having anode electrode, control grid electrode, screen-like electrode and cathode electrode, said tube when energized having a low amplification factor reciprocal, a source of high frequency oscillations connected with the control grid electrode of said tube, a source of modulating potentials connected with the control grid of said tube, and means for maintaining a desired relation between the amplitude of the high frequency waves and of the modulating potentials to control the degree of modulation including a rectifier of the controllable type connected at its input to a source of alternating current and at its output to the anode and screen-like and cathode electrodes of said tube to energize the same and a circuit energized by modulating potentials connected with said rectifier for controlling the rectifying action thereof. 10 15 20 25
